DESIGN FOR A STEERING POST SHROUD FOR A BICYCLE OR THE LIKE

John R. Morgan, Oak Park, Ill., assignor to
Sears, Roebuck and Co., Chicago, Ill., a corpo-
ration of New York

Application November 10, 1938, Serial No. 81,010

Term of patent 7 years

To all whom it may concern:

Be it known that I, John R. Morgan, a citizen
of the Republic of Guatemala, residing in Oak
Park, in the county of Cook and State of Illinois,
have invented a new, original, and ornamental
Design for a Steering Post Shroud for a Bicycle
or the Like, of which the following is a specific-
cation, reference being had to the accompanying
drawing, forming a part thereof.

Fig. 1 is a top plan view of a steering post

shroud for a bicycle or the like, embodying my
new design.

Fig. 2 is a side elevational view thereof.

Fig. 3 is a front elevational view of the same.

Figs. 4 and 5 are sectional views taken respec-
tively along the lines 4—4 and 5—5 of Fig. 2.

I claim:

The ornamental design for a steering post
shroud for a bicycle or the like, as shown.

JOHN R. MORGAN.
